ELECTRONIC TACHOMETER UTILIZING TUNED SIGNAL TRANSDUCER

Robert L. Reiner, West Caldwell, N.J.
(Glenwood Court, Bethany, Conn.)
Filed Nov. 22, 1960, Ser. No. 70,991

6 Claims. (Cl. 324—70)

My invention relates to tachometers, particularly to electronic tachometers, and has for its primary object to provide an improved electronic circuit for measuring the number of revolutions per minute of ignition systems ignited by spark plugs.

The need for a tachometer which would not require special calibration or knowledge of the number of cylinders in an engine when used with various types of ignition systems and particularly with respect to two cycle or four cycle ignition systems has resulted in the present invention which samples an electrical condition common to all ignition systems. My invention is unique in that I take advantage of the low impedance produced during the arc discharge to drive the signal impulse and thereby actuate or trigger the subsequent circuitry to result in a reading proportional to r.p.m. I, therefore, use the low impedance of the arc which is a reasonably constant parameter common to all ignition systems. Also, I sense this parameter electromagnetically through only one spark plug lead of the total number of spark plug leads required in an ignition system, so that the number of cylinders in the ignition system is immaterial.

In order to utilize this arc discharge for all types of ignition systems, including magneto, battery and electronic, it is necessary to sense the electrical force which sustains the arc. In this invention it is the sustaining current that maintains the arc, which is utilized as a signal source at a sensing transducer. In addition to the current associated with the arc or spark there is always an associated rapid rise or fall of potential. Consequently, to insure overall system stability it is necessary to isolate potential changes generated from other spark plugs in order to prevent their appearance as signals, and thereby when calibrated for two cycle operation enable my tachometer to be used on all two cycle engines regardless of the number of cylinders and, similarly, when calibrated for four cycle engines. This is important, since among the various ignition systems and during normal operation of a gasoline engine this change in potential varies over very wide limits, such that it would be impractical to try to use it as a means of signalling from one spark plug. Further, I avoid sensing potential changes at the spark plug wire which is necessarily done at a very high impedance level and which is consequently very sensitive to stray electrostatic pick-up particularly from other spark plugs or other ignition systems which may be nearby.

Also, when sensing electrostatic changes as a signalling means in conventional tachometers, capacitive coupling is usually used to produce a driving signal. In practice, any coupling capacitance in the signal circuit has been found to contribute to unsteady meter indication because of charging and discharging time constants. This occurs primarily during transient periods, either during changes in r.p.m. or loading on the gasoline engine. However, when sensing the current, as in my invention capacitive coupling is eliminated. My arrangement is effective during the arc discharge which is during a "short circuited" condition of the ignition system and, therefore, during a very low driving point impedance interval. The advantage of such sensing is negligible susceptibility to stray electrostatic pick-up and, by proper design of the sensing transducer, negligible loading at the ignition system. The transducer, which senses these current impulses at a spark plug and produces output signal pulses directly propor-

2

tional to the r.p.m. of the engine irrespective of the number of cylinders, is the most important component in the entire tachometer system. It was necessary in the design of the transducer to isolate the sensing coil from the signal coil, so that current produced at the signal coil by the current flowing through the sensing coil during an arc at the spark plug would dominate all other system noise, particularly, electrostatic.

It is therefore a further object of my invention to provide an improved tachometer that is unaffected by potential variations in an ignition system fired by spark plugs.

It is another object of my invention to provide an improved tachometer that is stable over a wide range of temperatures and that requires only one calibration when used with either two cycle or four cycle ignition systems.

It is still another object of my invention to provide an improved electronic tachometer that is simple in construction, reliable in operation and is economically manufactured.

It is a further object of my invention to provide an improved tachometer that maintains calibration accuracy over a wide input voltage swing.

Other and further objects will be obvious upon an understanding of the illustrative embodiment about to be described, or will be indicated in the appended claims, and various advantages not referred to herein will occur to one skilled in the art upon employment of the invention in practice.

In accordance with the present invention the foregoing objects are generally accomplished by providing an improved universal tachometer comprising a transistorized voltage pulse counter which is stabilized and regulated electrically, and a transducer which senses current pulses in a spark plug lead of a gasoline engine. The transducer, which may be located in the engine compartment and connected directly to the spark plug wire, senses each time the spark plug fires, advantage being taken of the low impedance produced during the arc discharge, and transmits a signal pulse by a shielded cable to the counter, which may be located on a dashboard of a vehicle or bulkhead of a boat and which converts these pulses into a steady meter reading with a linear scale calibrated in r.p.m.

A more thorough understanding of my invention may be obtained from a study of the following description of several specific embodiments. In the drawings:

FIG. 1 is a schematic diagram showing a signal transducer of my invention connected to a typical ignition system fired by a plurality of spark plugs.

FIG. 2 illustrates typical wave forms of an ignition system supplying a multi-cylinder engine through a distributor having a primary driving force of coil, magneto or electronic.

FIG. 3 illustrates typical wave forms of output voltage at the output terminals of the signal transducer.

FIG. 4 is a schematic drawing showing a counter circuit and indicating circuit of my invention, adapted to be connected to the signal transducer of FIG. 1 without capacitive coupling.

FIG. 5 is a schematic diagram of a composite tachometer circuit including complete signal transducer, counter and indicating circuits in its simplest form.

Referring now to the drawings, particularly to FIG. 1, there is shown a conventional ignition system having a storage battery 20, primary coil 21, secondary coil 22, breaker points 23 with timer-cam 24, which rapidly makes and breaks the circuit between the breaker points 23, and a condenser 26 which shunts the breaker points 23. A lead 27 connects a high voltage potential from the secondary coil 22 to a rotary arm 28 of a distributor 29 which includes terminals 31 over which the contact arm 28 rides, as is well known. Each of the terminals 31 is connected

to a spark plug 32 for each cylinder (not shown), so that the ignition system shown is for a four cylinder engine.

In the present invention connection of a signal transducer 33 is readily made to the ignition system either at the spark plug or the distributor, or by cutting the high voltage wire 27 along its length, so that the current flowing in the wire, when the spark plug 32 fires, will flow through the signal transducer 33. As seen in FIG. 1, the signal transducer 33 comprises a transformer 34 having a primary winding or sensing coil 36, bridged by a condenser 37 (which provides a low impedance), and a secondary winding or signal coil 38. The primary winding or sensing coil 36 is also bridged respectively to distributor terminal 31 and spark plug 32, say for the first cylinder of the engine, so that the signal transducer 33 is serially interposed between the distributor and the spark plug.

In order to minimize electrostatic impulses at the output of the transducer 33, the sensing coil 36 and the signal coil 38 are so constructed that the sensing coil 36 is physically separated from the signal coil 38 by sufficient physical distance to keep the electrostatic coupling to a very low value. This separation also helps prevent voltage breakdown. In a prototype of my invention the core material was constituted by an inexpensive ferrite rod (not shown) approximately three inches long; however, iron core material has been found to operate satisfactorily. In order to further reduce electrostatic sensitivity, the condenser 37 is bridged across the sensing coil 36, whereby electrostatic charging currents flowing between the spark plug 32 and ground are by-passed and cannot be confused as a true signal impulse. This condenser 37, during the low impedance arc discharge, has little shunting effect of the current produced thereby and a strong current signal is therefore magnetically coupled between the sensing winding 36 and the signal winding 38 of the signal transducer 33. In practice the signal transducer 33 is remote from the rest of the tachometer circuitry, since it is convenient to make connections at the distributor or spark plug lead within the engine cowl and locate the tachometer indicator and circuitry on the dashboard or other part of the boat or automobile, etc. The signal from the transducer 33 is connected by a shielded cable or twisted pair comprising leads 39 and 40 to a counter circuit 41, FIG. 4, in order to minimize electrostatic noise. It might be mentioned at this point that my tachometer comprises four distinct parts—a signal transducer 33; an interconnecting cable comprising leads 39 and 40; a counter circuit 41; and a visual indicating circuit 42.

Referring now to FIG. 4, the counter circuit 41 is shown as being based upon the properties of a driven blocking oscillator in which a transistor 43 is used as its active element rather than a vacuum tube. The principle by which a controlled pulse is produced is generally known by those versed in the art and can be briefly described as follows: transistor 43 has a base *b*, which is a control electrode corresponding to the grid of a vacuum tube, an emitter *e* which corresponds to the cathode and a collector *c* which corresponds to the plate of a vacuum tube. These elements form, in effect, switching contacts such that for an NPN transistor a positive current flow between the base *b* and the emitter *e* causes the collector-emitter contact to close allowing a large signal to flow. Similarly, the lack of a positive current flow between base *b* and emitter *e* causes the collector-emitter contact to open, whereby no signal current can flow. This, of course, is the ideal case. In practice, however, the transistor 43 is never fully an open circuit nor fully a short circuit. However, by driving the base *b* with a large positive current the transistor 43 can be made to approach a short circuit; and by applying a reverse current between base *b* and emitter *e*, in other words making the base *b* negative with respect to the emitter *e*, the transistor 43 can be made to approach an open circuit.

In this counter circuit 41, a diode 44, preferably of

silicon, is used to provide the reverse bias. Initially no current flows from the positive terminal of battery 20 through the indicating circuit 42 and winding 46 of transformer 47, since the transistor 43 is assumed open. If a small positive current is now made to flow, say from the transducer 33 through the base *b* of transistor 43, a voltage drop will be produced across the winding 46 of transformer 47, because the collector *c* is being driven towards the emitter *e* by the small current. This drop is coupled to winding 48 by transformer action and the drop across winding 48 is in such a direction as to reinforce the original positive current flow through the transistor base *b*, thereby making the current cumulative. Transistor 43 is then rapidly driven to saturation, so that the collector-emitter contacts can now be considered closed. The full battery voltage less the drop across diode 44 and condenser 45 now appears across winding 46 of transformer 47, thus causing a magnetizing current to flow, which current is proportional to the primary inductance of the transformer 47. The length of time that the transistor 43 remains saturated or closed is determined by the time that the magnetizing current continues to build up in the core of transformer 47. This, then, is the length of time for a unit energy impulse to flow through the indicating circuit 42. It can be shown that variations in battery supply voltage will shorten or lengthen the time of this impulse resulting in a constant energy situation regardless of battery supply voltage.

After this forward pulse of energy terminates, because of saturation of the core transformer 47, an amount of power, proportional to the volume of the core material of transformer 47, is released and produces a potential drop across both windings 46 and 48 of whatever magnitude is necessary to cause a discharging current to flow. This is the common "inductive kick" principle associated with the discharge of any magnetic core and, in all blocking oscillator circuits, can develop high voltages across the transistor 43. If these voltages are not properly controlled or limited, the transistor 43 can be ruined. Consequently, protection of transistor 43 is afforded through diodes 49 and 50, the first of which limits the reverse polarity of winding 48 to a few volts and the second of which provides an additional discharge path, as will be described hereinafter. A small resistor 51, not usually required, can be included as shown to speed discharge of the magnetic core and its subsequent reset to allow the cycle to repeat. Diode 49, in addition to providing transistor protection, has a primary function of transferring positive signal impulses from the signal winding 38 of transducer 33 to the base *b* of transistor 43 through a current limiting resistor 52. Once a strong enough positive signal is supplied from the signal winding 38 of the transducer 33 through diode 49 to the base *b* circuit of transistor 43, regenerative action takes place for driving transistor 43 full on. The upper end, as viewed in FIG. 4, of winding 48 is driven several volts positive to insure sufficient base *b* current flow in transistor 43. Diode 49 is then also used to decouple the signal winding 38 of the transducer 33, so that current produced by the positive drop across winding 48 flows through the base *b* circuit of transistor 43 rather than across the signal winding 38 of the transducer 33.

After a unit energy impulse has terminated, diode 49, as explained hereinbefore, and diode 50 are used to complete discharge paths for the energy contained in the core of transformer 47. The first discharge path may be traced from winding 48 of transformer 47 via lead 40, through winding 38 of transducer 33, over lead 39, diode 49, resistor 51 and back through winding 48. The other discharge path is from winding 48, over lead 40, diode 50 and thence via resistance 51 back through winding 48. In general, negative potential can be considered ground or earth; however, for the system to operate properly either battery polarity may be grounded and, if more convenient, the entire tachometer circuit can be left floating.

The indicating circuit 42 comprises a direct current sensing ammeter 53 and an integrating network of sufficiently long time constant to smooth a repetition of unit energy impulses into a steady direct current flow through the ammeter 53. Many configurations for producing this are possible, only one of which is shown and which comprises a resistor 54 in series with the ammeter 53 and a variable resistor 56 and condenser 45 each in parallel with said ammeter 53 and resistor 54.

The operation of the circuit will now be considered. Each time upon discharge of the selected spark plug (No. 1) a signal is produced which comprises current flow through the signal transducer sensing winding 36 with a corresponding voltage drop being produced therein and also in the signal winding 38. The signal is then coupled via leads 39 and 40 to the counter circuit 41, as described earlier, resulting in a unit of energy flow through the indicating circuit 42. The initial polarity of the voltage drop at the signal winding 38, because of the direction of the current flow through the sensing winding 36, is unimportant, since transformer 34 and condenser 37 form a high "Q" (quality) ringing circuit which helps the normally oscillatory arc current. Assuming that the initial signal applied to diode 49 is a negative going signal, it will be blocked by diode action of diode 49 and no appreciable current will flow until the signal oscillates to a positive going polarity which is proper signal polarity for triggering the counter circuit 41 into conduction. Condenser 37 forms a low impedance path, as described earlier, to by-pass electrostatic changing currents, so that a drop caused thereby does not appreciably appear across the sensing winding 36 of the transducer 33. Because in a practical signal transducer and associated cable electrostatic voltage transients generated by other spark plugs in the ignition system cannot be entirely eliminated, an unwanted signal is coupled through diode 49 to transistor 43 and this unwanted signal must be kept below a minimum threshold, as seen in FIG. 3, so that it cannot trigger the counter circuit into conduction. This is important, since such signals are not of consistently high amplitude and cannot be included in the calibration of even a single ignition system.

In this connection, condenser 57 with resistor 52 forms an integrating network of such time constant that these unwanted signals are reduced, as seen in FIG. 3, below the discrimination level afforded by diode 44 and therefore cannot trigger the circuit. Resistor 52 serves two additional purposes. It limits the peak positive drive current through the base *b* of the transistor 43, as explained earlier, and also with resistor 51 provides a collector circuit load impedance which is reflected into winding 46 by transformer action. As long as resistor 52 is made large with respect to the variations in the base *b* resistance of transistor 43 over a specific operating temperature range, the stability and accuracy of the entire circuit can be predictably controlled and no special compensation is required. In general, a value for resistor 52 and, by proper choice of primary inductance of transformer 47, pulse width can be selected to produce optimal transistor base drive and collector load, so that a practical meter operating current is produced. In general this may be one milli-ampere for full scale deflection to reflect a two cycle or four cycle r.p.m. rate of perhaps 6,000 or 8,000 resulting in a signal repetition rate from 3,000 to 8,000 pulses per second for full scale readings. After resistor 52 is chosen, condenser 57 is picked to produce the desired integrating time constant.

For each signal of positive going polarity applied to the transistor 43, closure of the latter sends a similar pulse through the indicating circuit 42. Each such pulse may be traced from positive potential of battery 20 over leads 59, 61, via meter 53, resistor 54, lead 62, winding 46, lead 63, closed collector-emitter contact, lead 64, diode 44, and thence back over leads 66, 40 and 67 to negative terminal of battery 20. Thus the series of pulses produced

by the spark plug and illustrated in FIG. 2, are translated by the transducer 34 into a series of closures of the transistor 43, which in turn produces a series of repetitive pulses that, as explained hereinbefore, are integrated into a steady reading at the meter 53, which reading is calibrated by resistance 56 into corresponding r.p.m. of the engine. To produce sufficient current flow through the diode 44 in the above-traced circuit, such that its inherent voltage drop of about 0.7 volt for a silicon device is achieved, a resistor 65 is connected at one end to the positive side of the battery 20 and at its other end to lead 64 between the emitter *e* contact and diode 44. If this resistor 65 is eliminated, the voltage drop across diode 44 because of leakage current flow in transistor 43 may not be sufficient to reverse bias the transistor at elevated temperatures with the consequence that the circuit will become a free running oscillator at these elevated temperatures.

In order to provide economical battery supply operation the function of the diode 44 of FIG. 4 can be replaced by a single battery cell 68, as seen in FIG. 5, and the resistor 65 of FIG. 4 eliminated. It is necessary that the battery 68 have a fairly constant voltage drop over its entire operating life, since variations in the bias voltage will directly affect accuracy. The current demand from the battery supply 68 during stand-by will not exceed the very small leakage current flow in transistor 43.

It is practical to operate my tachometer from an external battery having very low internal impedance, such as a 6 volt or 12 volt lead-acid storage battery 20. If dry cell batteries 69, as seen in FIG. 5, are employed for the power supply, a shunting condenser 71 is provided in order to insure the necessary low supply impedance, so that calibration accuracy can be maintained throughout the discharge life of the battery 69.

Referring again to FIG. 5, which illustrates simplified counter and indicating circuits 41' and 42', respectively, combined with the transducer circuit 33, it will be noted that the resistors 51 and 52 have been replaced by a variable resistor 72 and the diode 50 eliminated. The operation of FIG. 5 is otherwise substantially that described in connection with FIG. 4.

An example of component part values for a representative embodiment of FIGS. 1 and 4, exclusive of ignition circuit, is as follows:

Condensers:

37 ----- microfarad 0.02
 45 ----- do 400
 57 ----- do 0.01

Diodes:

44 - IN483
49 - IN805
50 - IN805

55 Resistors:

51	ohms	100
52	do	1,500
54	do	1,000
56	do	500
65	do	5,600

Transistor:

43 ----- (NPN type) -- 2N1059

Meter:

53 ----- ma. F.S. 0-1

Transformers

34, ferrite core—			
Winding 36	-----	turns	250
Winding 38	-----	do	150
47, saturable core—			
Winding 46	-----	turns	250
Winding 48	-----	do	500

The values listed hereinbefore are for a particular embodiment of the invention and are not to be considered as

limiting the invention. Also, it is to be understood that any other type of switching means provided by the NPN type junction transistor might be substituted therefor without departing from this invention. As various changes may be made in the form, construction, and arrangement of the parts herein, without departing from the spirit and scope of the invention and without sacrificing any of its advantages, it is to be understood that all matters are to be interpreted as illustrative and not in any limiting sense.

What is claimed is:

1. In an electronic tachometer for an engine having an ignition circuit fired by a spark plug, a sensing coil connected serially to said spark plug in a high voltage circuit of said ignition circuit, a condenser connected in parallel with said sensing coil for providing a low impedance path for current discharges of said spark plug and for providing a time integral of each of said current discharges, whereby the current discharges are transformed into a series of constant peak amplitude signal voltages, an elongated conductive rod carrying said sensing coil at one end thereof, a signalling coil carried by said rod at its other end, whereby said sensing coil and said signalling coil are physically separated from each other so as to avoid arcing, said signalling coil being effective to isolate effects of said noise currents and to transform said constant peak amplitude signal voltages, said sensing and signalling coils being solely electromagnetically coupled, a tuned counter circuit responsive to said transformed signal voltages, said counter circuit including transistor switching means, said transistor switching means including an emitter, collector and base connections, and a meter circuit responsive to said counter circuit for indicating said spark plug discharges and correspondingly the speed of said engine.

2. In an electronic tachometer according to claim 1, wherein said sensing coil serially connected with said spark plug senses each discharge of the spark plug and said signalling coil signals each said discharge to the counter circuit, and a diode serially interposed between said signalling coil and said base connection of said transistor switching means for providing positive current flow between said base and emitter connections of said transistor switching means at each said discharge of said spark plug.

3. In an electronic tachometer according to claim 2, wherein a resistor is connected in series with said diode and base connection of said transistor switching means.

4. In an electronic tachometer according to claim 3, wherein a condenser is connected at one terminal to said resistor and at its other terminal to a terminal of said signalling coil to provide with said resistor an integrating network for reducing unwanted signals.

5. In an electronic tachometer for an engine having an ignition circuit fired by a spark plug, a tuned transducer

serially connected to said spark plug in a high voltage circuit of said ignition circuit, said transducer including a capacitor and a sensing winding connected in parallel, said capacitor providing a low impedance path for current discharge of said spark plug and providing a time integral of said current discharge, whereby the current discharge is transformed into a constant peak amplitude signal voltage, said capacitor also providing a shunt by-pass for electrostatically coupled noise currents from adjacent spark plug conductors of the ignition circuit, said transducer also including a signaling coil for isolating effects of said noise currents and for transforming said constant peak amplitude signal voltage, said sensing and signaling coils being solely electromagnetically coupled, a tuned counter circuit responsive to said transformed signal voltage, and an indicating circuit responsive to said tuned counter circuit.

6. In an electronic tachometer according to claim 5, wherein said tuned counter circuit includes filter means for accepting said transformed signal voltage and for rejecting said effects of said noise currents.
